Howson & Howson

UNITED STATES PATENT OFFICE.

HENRY N. FRICK, OF PHILADELPHIA, PENNSYLVANIA.

GREASE-CUP.

1,296,944.

Specification of Letters Patent. Patented Mar. 11, 1919.

Application filed December 6, 1917. Serial No. 205,807.

To all whom it may concern:

Be it known that I, HENRY N. FRICK, a citizen of the United States, residing in Philadelphia, Pennsylvania, have invented 5 certain Improvements in Grease-Cups, of which the following is a specification.

My invention relates to grease cups, more particularly the type employed upon automobiles and where a full charge of grease 10 is forced into the bearing at one operation; and one object of my invention is to provide a structure of few parts, economical in construction and highly efficient in operation. A further object of my invention is 15 to provide a grease cup with a cap that may be thrust into position with respect to the body of the cup, and a still further object is to provide automatic locking means for the cap when the latter is thrust into place; 20 such locking means being disposed between the cup and the cap and wholly concealed by the latter.

These and other features of my invention are more fully described hereinafter, reference being had to the accompanying drawings, in which:

Figure 1, is a perspective view of my improved grease cup showing the parts of the same detached.

Fig. 2, is a sectional view of the same, and Figs. 3 and 4, are fragmentary sectional views illustrating modified constructions within the scope of my invention.

My improved grease cup comprises a cup proper having a body 1 and a threaded end 2 whereby it may be secured in its place of use, with an internal chamber 3 receiving the grease. As shown in Fig. 1, the body is grooved at 4 near its upper edge for the 35 reception of a spring locking ring 5, which serves as the means for retaining the cap 6 in place; the latter being grooved at 7 on its inner wall to provide a shoulder 8 so that when it is set in place the spring ring 40 5 will engage said shoulder 8 of the cap, as clearly shown in Fig. 2.

The body is provided with a flange 9, and the end of the wall of the cap preferably engages the top of this flange, as indicated in Fig. 2. The inner edge of this wall may be beveled, as indicated at 10, forming a little pocket 11 adjacent the flange 9 which serves to catch any dirt and dust that may collect on the exterior of the body, 1, of the cup 45 and that finds its way past the end of the

flange, 9 and prevent the same passing up the outer wall of the body inside the cap and gaining access to the body of grease within the latter. The fit between the cap and body should be quite close, but at the 60 same time a proper working fit so that no difficulty will be had in assembling the parts. To facilitate setting the chambered body 1 in position, the upper edge of the same may be notched, as indicated at 12, for engagement by a screw driver or other suitable form of setting tool.

In lieu of having the cup body 1 carry the spring locking ring, it may be carried by the cap, as shown in Fig. 3; in which 70 case the body of the cap near the upper wall of the same will be thickened as at 6^a, and grooved at 7^a to receive a spring locking ring 5^a. The cup body will have the same groove 4, as indicated in Figs. 1 and 2, 75 with which the spring locking ring 5^a will engage when the cap is thrust into place.

Another arrangement within the scope of my invention is shown in Fig. 4, where the cup 1 is provided with a groove 4^a near the 80 base of the same to receive the spring locking ring 5; the cap 6 in such case being provided with a groove 7^b and shoulder 8^a, of the character shown in Figs. 1 and 2, but disposed nearer the beveled edge 10 thereof.

In all instances the retaining means for the cap are disposed between the cup body and the cap and are wholly concealed by the latter. In some instances, it may be desirable to combine the modifications illustrated in Figs. 3 and 4, in a structure in which the cap carries the locking ring, as in Fig. 3, but disposed near its beveled edge, as in Fig. 4.

The spring ring is, of course, a split structure, and I prefer a lapped joint 13, in which the meeting faces of the lapping parts are in the axial plane of the ring body. This ring is designed to provide a close fit between the walls of the parts of the structure at its point of application thereto in the manner of a piston ring whereby it may act as a perfect closure to prevent any access of dirt or dust, on the one hand, or grease 95 passing down the walls of the cup, on the other hand when the filled cap is applied to the cup. It is therefore essential that the faces of the lapping parts of the ring shall be in a plane coincident with its point of contact with the wall of the body or the cap,

as the case may be, to insure a perfect closure.

The parts of the structure may be cast and shaped in any usual way, or the body may 5 be cast and the cap made of sheet metal spun into shape, or both parts may be of pressed metal. In practice, the cap is filled with grease and then placed over and pressed down upon the body of the cup, which act 10 will cause the full charge of grease to enter the chamber of the cup by a single push of the cap; forcing out any grease that may be present therein and driving it to the proper point for distribution. Further flow of 15 grease is by gravity in the usual manner.

While I have referred to a grease cup in describing my improved structure, it will be understood that the improvements constituting my invention may be employed in connection with oil cups; hence the term "grease 20 cup" in the claims is to be construed as broad enough to cover an oil cup or a grease cup or, in fact, any cup or equivalent structure designed to carry a body of lubricating material 25 and having the features constituting my invention.

I claim:

1. The combination in a grease cup, of a body having an open top and having a groove 30 in its outer wall, a cap closely fitting the body and designed to force a full charge of grease into the cup at one operation, said cap having a groove in its inner wall, and a spring ring carried by the body and adapted 35 to engage the groove of the cap to lock the cap in place, said body and cap telescopically fitting and said body having an exterior flange opposing the lower edge of the cap and against which the said edge of the cap 40 is designed to seat when forcing the full charge of grease into the cup.

2. The combination, in a grease cup, of a body open at the top and having a groove in its inner wall adjacent the top thereof, a 45 cap fitting the body and having a groove in its inner wall, and a spring ring carried by the body and adapted to engage the groove of the cap whereby the latter may be locked in place, said body and cap telescopically 50 fitting one within the other and said cap adapted to force a full charge of grease into the cup at one operation, said spring serving as a scraper to clean the inner wall of the cap during the telescopic movement of the latter.

55 3. The combination, in a grease cup, of a chambered body having a threaded end, a flange adjacent the threaded end; said body having a groove in its outer wall, a cap fitting the body and having a groove in its

inner wall, and a spring ring carried by the 60 structure and engaging said grooves whereby the cap may be locked in place; said cap having an interior beveled wall, and the bottom edge of the cap adjacent said beveled wall being adapted to engage the flange of 65 the chambered body.

4. The combination, in a grease cup, of a chambered body having a threaded end, a flange adjacent the threaded end; said body having a groove in its outer wall adjacent 70 the top of the same, a cap fitting the body and having a groove in its inner wall, and a spring ring carried by the structure and engaging said grooves whereby the cap may be locked in place; the bottom edge of the 75 cap being shaped to engage the flange of the chambered body.

5. The combination, in a grease cup, of a chambered body having a threaded end, a flange adjacent the threaded end; said body 80 having a groove in its outer wall, a cap fitting the body and having a groove in its inner wall, and a spring ring carried by the structure and engaging said grooves whereby the latter may be locked in place; the bottom edge of the cap being adapted to engage 85 the flange of the chambered body, and the spring ring having a lapped joint with the meeting faces of the lapping parts in the plane of contact with the engaging wall. 90

6. In a grease cup, a body recessed to receive grease, a cap closely fitting the same and telescopically movable with respect to the recessed body; said cap adapted to force a full charge of grease into the recessed body 95 at one operation; the meeting walls of said members being plain surfaced for the greater portion of their extent and having registering recesses, and a spring ring carried by one of said members and contacting with the 100 other when the cap is forced into place; said ring occupying both of the recesses and locking the members together when the cap is in place.

7. The combination, in a grease cup, of a chambered body having a groove in its outer wall, a cap telescopically fitting the chambered body and having a groove in its inner wall, and a spring ring carried by one 105 of said members and contacting with the 110 groove of the other when the cap is forced into place and locking said members together; said spring ring having a lapped joint with the meeting faces of the lapping parts in the plane of contact with the engaging wall. 115

HENRY N. FRICK.
